(57) **CLAIM**

The ornamental design for an indoor wall with built-in home appliances, as shown and described.

DESCRIPTION

FIG. 1 is a front perspective view of the indoor wall with built-in home appliances showing our new design;

FIG. 2 is a front view thereof;

FIG. 3 is a rear view thereof;

FIG. 4 is a left view thereof where the right view is a mirror image;

FIG. 5 is a top view thereof;

FIG. 6 is a bottom view thereof;

FIG. 7 is a reference view showing the state of use that the built-in home appliances are installed in the claimed design;

FIG. 8 is a reference view showing the state of use that the front upper cover is being pushed inside;

FIG. 9 is a front perspective view in a condition that the front upper cover has been pushed inside;

FIG. 10 is a front view of FIG. 9;

FIG. 11 is a rear view of FIG. 9;

FIG. 12 is a left side view of FIG. 9 where the right view is a mirror image;

FIG. 13 is a top view of FIG. 9;

FIG. 14 is a bottom view of FIG. 9;

FIG. 15 is a reference view showing the state of use that the front bottom cover is being raised;

FIG. 16 is a front perspective view in a condition that the front bottom cover has been raised;

FIG. 17 is a front view of FIG. 16;

FIG. 18 is a rear view of FIG. 16;

FIG. 19 is a left side view of FIG. 16 where the right view is a mirror image;

FIG. 20 is a top view of FIG. 16;

FIG. 21 is a bottom view of FIG. 16; and,

FIG. 22 is a reference view showing the state of use that the television and audio which is installed at the front of the claimed design can be used by raising the bottom cover of the front.

(Continued)

The broken lines depict portions of the indoor wall with built-in home appliances that form no part of the claimed design. The dash-dot broken lines define the boundary of the claimed design and form no part thereof.

1 Claim, 22 Drawing Sheets
